UNITED STATES PATENT OFFICE.

BURWELL C. H. SIMPSON AND CARL F. CRECELIUS, OF FALMOUTH,
KENTUCKY.

HOLDER FOR TOOTH-BRUSHES AND TOOTH-POWDER.

SPECIFICATION forming part of Letters Patent No. 699,983, dated May 13, 1902.

Application filed October 12, 1901. Serial No. 78,430. (No model.)

To all whom it may concern:

Be it known that we, BURWELL C. H. SIMPSON and CARL F. CRECELIUS, citizens of the United States, residing at Falmouth, in the county of Pendleton and State of Kentucky, have invented a certain new and useful Improved Holder for a Tooth-Brush and Tooth-Powder, of which the following is a full and complete specification, such as will enable

those skilled in the art to which it appertains to make and use the same.

This invention has for its object to provide means for carrying a tooth-brush and tooth-powder in the pocket or in a hand-bag or satchel or for forwarding the same through the mails, and more particularly for providing a simple, cheap, readily-constructed, and perfectly-operating device by which the brush may be held in position in the holder against accidental removal and tooth-powder also held in immediate relation thereto, but without danger of loss, spilling, or contamination in all circumstances of the use of the holder.

With these and other minor objects in view our invention broadly consists, primarily, of a holder for a tooth-brush provided with a main compartment to receive the bristles or body of the brush at one end of the holder and a tooth-powder-containing compartment within the opposite end or portion of the holder and projecting therein in such relation thereto as to form at one side of the said tooth-powder-containing compartment and in longitudinal continuation with the main brush-holding compartment a recess or supplementary compartment for the handle.

Secondarily, it consists of such a holder formed with the several compartments in the manner stated and means for closing the tooth-powder-containing compartment, while leaving the main or brush-containing compartment open and the brush retained therein by friction with the walls of the main compartment and the tooth-powder-containing compartment, respectively, where they range in parallel relation and in suitably-proportioned proximity to form a longitudinal handle-containing compartment.

Further and finally, our invention consists in the novel construction and arrangement of parts hereinafter fully described and claimed.

In the accompanying drawings, forming part of this specification, in which like letters of reference designate corresponding parts in the several views, Figure 1 is a perspective view of a device embodying our invention, a portion of the tooth-powder-containing compartment being broken away at one end. Fig. 2 is a side elevation of the device, a portion of the front wall being broken away or sectioned to show the method of removing the tooth-brush; and Fig. 3 is a section on the line xx of Fig. 1.

In the practice of our invention we construct a rectangular holder A of a length approximately equal to the length of an ordinary tooth-brush or of the particular tooth-brush which the holder may be designed to contain of a width approximately equal to the depth of the brush or its bristle portion and of a depth equal to or slightly greater than the width of the brush at its broadest part. This holder or box comprises a base provided with upwardly-projecting side walls A' and end walls A². Laying the brush B in this rectangular holder in the manner shown in the drawings, so that its handle B' lies in contact with one of the sides A' of the holder, we select one end of the holder to constitute the main compartment for the body or bristle portion of the brush, and in the opposite end or portion of the holder we secure to the base thereof and to the end wall A² a vertical longitudinal partition C, which we extend toward the center of the holder to a point appreciably below the bristle portion of the brush, and we turn this partition around to form a semicircular or rounded extension or end C', which we secure to the base of the holder and to the front wall A' thereof.

The partition C is equal in height to the walls A' and end pieces A² and ranges parallel with the former on a line rearwardly of the transverse center of the holder, so that the tooth-powder-containing compartment D, formed in the front of the said partition between the end A² of the holder and the rounded extension C of the partition, will occupy in width the greater portion of the end of the holder in which said compartment is formed and will leave rearwardly of the partition C, between the same and the rear wall A' of the

holder, a narrow longitudinal compartment E of substantially equal width throughout and adapted to receive neatly therein the handle of the tooth-brush, whereby the brush 5 is retained in position by the contact of its handle B' with the rear wall A'. The walls and partition and, in fact, the whole of the holder are preferably formed of thin sheet metal more or less flexible or yielding, and 10 the lodgment of the handle between the wall A' and the partition C does not injure the handle nor wedge it so tightly as to prevent purposed removal.

Approximately at the center of the partition C and upon the upper edge thereof we 15 secure a small hinge F, by means whereof a lid G is pivotally connected to the said partition. This lid is of a width to cover the tooth-powder-containing compartment D and is 20 provided upon its outer or free longitudinal edge with a downwardly-directed flange G', adapted to engage the outer edge of the front wall A' and formed with a notch G², adapted to engage a projection G³ upon the front wall 25 A' to form a spring-catch. Upon the outer end of the lid is a flange G⁴, which engages on the outer side of the end wall A², and the opposite or inner end is struck downwardly at the corners to make the end rounded and 30 provided with two depending lugs G⁵, which engage the rounded end E' of the partition C.

The operation of the device will be readily understood from the foregoing description, taken in connection with the accompanying 35 drawings, and the advantages resultant from the use of our invention will be manifest to all who are conversant with devices of this character.

The compartment D is filled with tooth-powder and the lid G thereof closed. The 40 flanges G' and G⁴ will engage the outer walls of the holder and prevent egress of the contents of the compartment D, and both of the projections or lugs G⁵ will engage the rounded 45 edge of the partition C and prevent the tooth-powder from running over in the main compartment of the holder and will also engage the said end to limit the movement of the lid G. The compartment D, it will be observed, 50 is formed from the walls of the main holder and the partition C, and when the lid G is closed the partition C will be held or steadied in proper vertical position. The tooth-brush is then placed in the holder, as shown in the 55 drawings, so that its bristle portion lies upon one side thereof in the main compartment of the holder, and said handle fits neatly and frictionally in the narrow longitudinal compartment E, formed by the partition C and the rear wall A'. Not only is relative movement 60 of the brush in its holder prevented by the mounting of the tooth-powder-containing compartment within the said holder by preventing lateral displacement of the brush 65 therein, but, moreover, the brush is retained against accidental removal or dropping from the holder by its frictional position in the

said narrow longitudinal compartment D. By the form and arrangement of this compartment it will be seen that the main compartment or opposite end portion of the holder is left somewhat longer than the length of the bristle portion of the brush, and, as shown in Fig. 2, this permits the finger to be inserted between the bristle portion of the 70 brush and the rounded end of the tooth-powder-containing compartment, so as to catch the finger beneath the usually-narrowed portion or neck of the brush to remove the same from the holder. It will especially be observed that as the brush is held positively in the narrowed longitudinal compartment E the bristles will be held out of contact with the front wall of the holder, preventing injury thereto or contamination thereof by such 85 contact. The brush being removed and it being desired to use the same, the lid G is raised and powder dipped out with the brush in the customary manner. The tooth-powder-containing compartment may after use 90 of sufficient tooth-powder be closed and its lid fastened by the catch or notch and projection and this without closing the main holder or brush-containing compartment. Hence notwithstanding the fact that the 95 tooth-powder is maintained immediately at hand and its receptacle made a part of the brush-holder nevertheless the powder will not be exposed continuously during the absence of the brush from the holder, as there is no temptation to leave the lid of the device open until ready to put back the brush. It will, moreover, be observed that no devices for fastening the brush are required and no cover is necessary for the main body of the 100 holder, as the brush is self-retained in position and yet is protected and substantially covered by the base and walls of the holder, and the moisture of the brush after use is not likely to be communicated to adjacent 105 objects when the device is placed in the pocket or in a satchel.

Having thus fully described our invention, what we claim as new, and desire to secure by Letters Patent, is—

1. A holder for a tooth-brush and a tooth-powder comprising a rectangular receptacle formed of a base of approximately the length of the tooth-brush and of a width approximately equal to the depth of the bristle portion thereof, and having upwardly-projecting walls of a height at least equal to the width thereof, a tooth-powder-containing compartment formed in the said rectangular receptacle at one end thereof and projecting rearwardly beyond the transverse center thereof whereby the rear or inner wall of the compartment forms with the rear or outer wall of the main holder a narrow longitudinal compartment continuous with the main or opposite end portion of the compartment comprised by the receptacle, and ranging parallel with the said rear wall of the holder and in such relation thereto as to operate in con-

nection therewith to hold the handle of the brush whereby to retain the same in the holder against displacement; and the said tooth-powder-containing compartment being 5 of a length to leave a space between the bristles of a tooth-brush and the inner end of the compartment for the entrance of a finger beneath the neck of the brush; and means operating in connection with the tooth-pow- 10 der-containing compartment and the outer wall of the holder whereby to close the said tooth-powder-containing compartment only, leaving the main or brush-holding compartment open.

15 2. A holder for a tooth-brush comprising a receptacle formed of a rectangular base of a length approximately equal to that of an ordinary tooth-brush and of a width approxi- 20 mately equal to the depth of the bristle portion thereof and formed with upwardly-projecting walls in height at least equal to the width of the brush and adapted to receive the entire brush within the same when the handle of the brush is placed in contact with one of 25 the longitudinal walls of the said receptacle; a tooth-powder-containing compartment formed of a longitudinal partition ranging within the main receptacle or compartment and at one end thereof parallel with the said 30 longitudinal wall of the holder and rear- wardly of the transverse center of the holder and in such relation to the said longitudinal wall as to operate in connection with the said longitudinal wall to hold the handle of the 35 brush whereby to retain the same in the holder against displacement, the said partition being secured to one end wall of the

holder and to the base and ranging longitudinally to a point appreciably below the position of the bristles in the operative position 40 of the brush in the holder whereby a finger may be inserted between the said bristles and the end of the partition beneath the neck of the brush to remove the same from the holder; the inner end of the said partition being turned 45 around to form a semicircular or rounded end wall for the tooth-powder-containing compartment, and being secured to the base and to the front wall of the main receptacle and the said partition, and its rounded end or ex- 50 tension being of equal height with the walls of the brush-holder; and a lid for the tooth-powder-containing compartment only, the said lid being hinged to the partition and ex- 55 tending to the front wall of the holder and provided with a longitudinal flange adapted to connect the said lid to the said front wall, means upon the said flange and upon the said front wall for fastening the lid down, a flange upon one end of the lid overlapping the outer 60 end of the main receptacle and downwardly-projecting corner-lugs upon the opposite inner end of the lid engaging the rounded or semicircular end or extension of the partition.

In testimony that we claim the foregoing as 65 our invention we have signed our names, in presence of the subscribing witnesses, this 8th day of October, 1901.
